UNITED STATES PATENT OFFICE.

GUSTAVE LIDSEEN, OF CHICAGO, ILLINOIS.

OIL-CAN-SPOUT CLOSER.

1,401,161.

Specification of Letters Patent. Patented Dec. 27, 1921.

Application filed April 29, 1920. Serial No. 377,442.

To all whom it may concern:

Be it known that I, GUSTAVE LIDSEEN, a citizen of the United States, and a resident of the city of Chicago, in the county of Cook and State of Illinois, have invented certain new and useful Improvements in an Oil-Can-Spout Closer; and I do hereby declare that the following is a full, clear, and exact description of the same, reference being had 10 to the accompanying drawings, and to the numerals of reference marked thereon, which form a part of this specification.

This invention relates more particularly to an improved type of a closure mechanism 15 adapted to be secured on the outer end portion of an oil can spout for normally holding the mouth of the spout closed by a spring-impelled lever.

It is an object of this invention to provide 20 a spring-impelled pivoted stop for automatically closing the end of an oil can spout.

Another object of the invention is to provide 25 a spout with a removable means for automatically closing the outlet end of said spout.

A further object of the invention is to provide 30 an oil can spout with a spout closer having a pivoted thumb piece provided with a cap adapted to engage over the outlet end 35 of the spout to normally prevent leakage from the spout should the oil can accidentally be overturned.

It is an important object of this invention to provide 40 an oil can with a simple and improved type of a spout closer adapted to be removably clamped in position on the oil can spout to normally close the open end of said spout.

Other and further important objects of 45 this invention will be apparent from the disclosures in the specification and the accompanying drawings.

The invention (in a preferred form) is 50 illustrated in the drawings and hereinafter more fully described.

On the drawings:

Figure 1 is an elevation of an oil can the 55 spout of which is equipped with a closer embodying the principles of this invention.

Fig. 2 is an enlarged elevation of the spout closer with the spout partly broken away.

Fig. 3 is an enlarged detail sectional view 60 taken on line 3—3, of Fig. 1.

Fig. 4 is a fragmentary detail section taken on line 4—4, of Fig. 3. 55

Fig. 5 is an enlarged fragmentary detail section taken on line 5—5, of Fig. 2.

Fig. 6 is an enlarged detail section taken on line 6—6, of Fig. 1.

Fig. 7 is a side elevation of a modified 60 form of a closer shown attached to a curved oil can spout.

As shown on the drawings:

The reference numeral 1, indicates an oil can having removably engaged thereon a 65 tapered spout 2.

The spout closer of this invention comprises a split clamping collar or sleeve 3, provided with two parallel lugs or flanges 4, which are apertured to permit a screw 5, to 70 be threaded therethrough for tightly drawing said lugs together to clamp the sleeve 3, in position on the spout 2, against movement. Integrally formed at the lower end of the sleeve 3, and opposite the lugs 4, are 75 two parallel lugs or arms 6, which support a pin 7.

Pivottally engaged on the pin 7, between the arms 6, are two apertured lugs or projections 8, formed by providing a notch or 80 opening in the lower end of a flat metal lever 9. Coiled around the pin 7, within the lever notch is a coiled spring 10, one end of which bears against the spout 2, while the other end projects outwardly through said notch 85 and is hooked to engage the lever 9, to normally hold said lever in a closed position. The upper end of the lever 9, is bent over at an angle to form a plate or flange 11. Integrally formed on the flange 11, is a raised 90 or elevated cap or head 12, within which is seated a cork or rubber closure disk or packing pad 13. Lugs 14, are struck from the flange 11, and are bent or curled inwardly beneath the pad 13, to hold the same 95 secured in position.

Fig. 7, shows a modified form of a spout closure, the construction of which is substantially identical with that of the closer already described with the exception that 100 the lugs 6, are longer, and the top plate or flange 11, is but slightly bent with respect to the lever 9, to permit the closure pad 13, to engage against and close the open end of an oil can spout 15, the end of which is 105 bent or curved as at 16.

The operation is as follows:

Normally the spring 10, acts to hold the lever 9, in the full line position of Fig. 1, with the closure pad or disk 13, seated over the open discharge end of the oil can spout to close the same. To use the oil can it is tilted downwardly or inverted and the lever 9, is retracted by a person's thumb, into the dotted line position of Fig. 1, thereby 10 moving the closure cap out of engagement with the discharge end of the oil can spout 2. Oil is thus permitted to be forced from the oil can spout.

To stop the flow of oil from the can spout 15 the lever is released and is automatically returned to normal closed position by the spring 10. The top of the cap 12, affords a suitable projection or rest permitting the thumb or finger of a person using the oil 20 can to obtain a suitable hold or grip on the lever to permit actuation thereof.

The operation of the modified form of the device shown in Fig. 7, is substantially the same as that already described.

25 I am aware that numerous details of construction may be varied through a wide range without departing from the principles

of this invention, and I therefore do not propose limiting the patent granted otherwise than necessitated by the prior art.

30

I claim as my invention:

The combination with an oil can spout, of a member engaged thereon, means for clamping said member in place on said spout, arms integrally formed on said member, a pin supported by said arms, a lever pivotally engaged on said pin, a flange integrally formed at an angle on the end of said lever, a cap formed thereon, a closure pad seated in said cap, means struck from said flange to hold said closure pad in place, and a spring coiled around said pin and engaging said spout and lever to normally hold said lever in a position wherein said closure pad is adapted to seat over the end of said spout 45 to close the same.

In testimony whereof I have hereunto subscribed my name in the presence of two subscribing witnesses.

GUSTAVE LIDSEEN.
